UNITED STATES PATENT OFFICE.

LOUIS N. D. WILLIAMS, OF OGONTZ, PENNSYLVANIA, ASSIGNOR OF ONE-HALF TO ROBERT W. SCOTT, OF PHILADELPHIA, PENNSYLVANIA.

KNITTED FABRIC.

SPECIFICATION forming part of Letters Patent No. 789,581, dated May 9, 1905.

Application filed March 30, 1904. Serial No. 200,820.

To all whom it may concern:

Be it known that I, LOUIS N. D. WILLIAMS, a citizen of the United States, residing in Ogontz, Pennsylvania, have invented certain 5 Improvements in Widened Knitted Webs and in the Production of the Same, of which the following is a specification.

My invention consists of a certain shaped or fashioned knitted web and a certain method 10 of producing the same, the web having widening-wales introduced without the use of transfer-points for conveying stitches from needle to needle or of a filling-up point for conveying an already-formed stitch to a vacant needle, the formation of eyelet-holes or gaps in the web at the points where the widening-wales are begun being also avoided.

The present invention is a modification of that forming the subject of Letters Patent 20 No. 614,349, granted November 15, 1898, to Robert W. Scott.

In the accompanying drawings, Figure 1 is an exaggerated view of sufficient of a piece of knitted fabric to illustrate my present invention. Figs. 2, 3, 4, and 5 are views illustrating the manner in which each widening-wale is introduced, and Figs. 6, 7, and 8 are diagrams illustrating different dispositions of needles which may be adopted in machines designed 25 for the production of my improved fabric.

In Fig. 1 I have shown thirteen successive courses of a web into which six widening-wales have been introduced, three on each side of 30 the central line $\alpha\alpha$, although the widening may only be on one side, if desired. In the first, second, third, and fourth courses of the web each side of the latter is composed of two standing wales a^1 a^2 and four bordering-wales b^1 , b^2 , b^3 , and b^4 , an additional standing wale a^3 being introduced in the sixth course, a second additional standing wale a^4 being introduced in the ninth course, and a third additional standing wale a^5 being introduced in the twelfth course. The opposite portions of the web in the first, second, third, and fourth courses are separated by floating threads a , or, as they may be more properly termed, "elongated 35 sinker-wale courses," and the length of these

sinker-wale courses is gradually diminished 50 as the opposite portions of the web are widened by the introduction of the additional wales until finally the two portions of the web join and form a continuous fabric, although this is not essential. The bordering-wales may 55 represent the edge portions of two flat webs, or they may be the opposite edge portions of a single web, and instead of being connected by elongated sinker-wale courses they may in some cases have selvage edges. The opposite 60 edges of the narrow web or webs and of the portions in which the widening has been effected can be united by means of an ordinary looping-machine or by sewing or in any other available manner, the sinker-wale courses a 65 being removed, if desired.

So far as described the present fabric is similar to that of the patent before referred to, the main difference between the two fabrics being in the manner of introducing the widening-wales into the fabric. In the patented fabric the innermost of the bordering-wales was crossed by each widening-wale at the point of introduction of the same into the web; but in the present fabric the initial course 70 of the widening-wale engages with an elongated stitch drawn from a preceding course of one of the bordering-wales, preferably the innermost wale, and also with a laterally-expanded stitch of a following course of said 75 bordering-wale, which latter stitch may thus be said in a measure to cross the widening-wale, while at the same time it preserves its proper relation to the other bordering-wales. Thus, as shown in Fig. 1, a stitch is drawn 80 from course 4 of the wale b^1 into course 5 to engage the first widening-wale a^3 in course 6, while in course 5 wales b^1 , b^2 , b^3 , and b^4 are shifted laterally to the extent of one wale, and in this course the wale b^1 is laterally expanded, so as to engage not only with wale b^1 in course 6, but also with wale a^3 in said course. The widening-wale a^4 in course 9 engages not only with the elongated bordering-wale b^1 drawn from course 7 into course 8, but also 95 with the laterally-expanded wale b^1 in course 8, and the widening-wale a^5 in course 12 engages with the elongated bordering-wale b^1 ,

drawn from course 10 into course 11, and also with the laterally-expanded wale b' in course 11. The manner of effecting this intermeshing of the wales will be understood on reference to Figs. 2, 3, 4, and 5. In Fig. 2, A' and A^2 represent the end needles of the set for the production of the standing wales, and B' , B^2 , B^3 , and B^4 represent the needles of the set for forming the bordering-wales. The needles or 5 the stitch-holding portions of the needles of the set for producing the standing wales and the like portions of the needles of the set for producing the bordering-wales are movable relatively to each other both in the direction 10 of the arrow y , Fig. 2, and in the directions of the arrow x , Fig. 2, although said bordering-needles or the stitch-holding portions of the same may be permanently offset in the direction of the outward-pointing arrow x in 15 respect to the like portions of the standing-wale needles to an extent which will not interfere with the delivery of the knitting-yarn to both sets of needles by the same yarn-guide. Preferably the stitch-holding portions of the 20 bordering-needles have movement in respect to the like portions of the standing-wale needles, this being a more convenient arrangement than the reverse construction. During 25 the knitting of the narrow fabric the needles 30 occupy the relation to each other shown in Fig. 2; but when it is desired to effect a widening of the web the needles B' to B^4 are first moved in the direction of the arrow x away from the needles A' A^2 , as shown in Fig. 3, so as to pull up 35 the preceding course of bordering-wales into line with the standing wales on the needles A' and A^2 . Thus, as shown in Fig. 3, course 3 of the bordering-wales b' to b^4 is pulled into line with course 4 of the standing wales on 40 needles A' A^2 . An additional standing-wale needle A^3 is then inserted into the pulled-up stitch of the wale b' , and the needles B' to B^4 are then moved in the direction of the arrow y to the extent of one wale and then permitted 45 to resume their former position in line longitudinally with needles A' and A^2 , as shown in Fig. 4. The effect of this movement is to restore all of the courses of the bordering-wales into line with the corresponding courses of the 50 standing wales, except that course 3 of wale b' is drawn into course 4 and engaged with the new needle A^3 , with which also engages the wale b' of course 4, said latter wale being also displaced laterally into line with wale b^2 55 of course 3, while wales b^2 and b^3 of course 4 are in line with wales b^3 and b^4 of course 3, wale b^4 of course 4 being outside of wale b^4 of course 3. In the production of course 5, therefore, the new wale a^3 will engage not only 60 with the wale formed by the elongation of wale b' of course 3, but will engage also with the wale b' of course 4, the latter by reason of the movement of the needles B' to B^4 being stretched so as to cross the wale a^3 , as 65 shown in Figs. 1 and 5.

The number of wales in the band which borders the widened portion of the web may be varied as desired without departing from my invention.

In a web fashioned in the manner described 70 each wale which starts a widening engages a wale which is drawn from a bordering-wale of the fabric, and in this respect my invention differs from that class of widened knitted fabrics in which the stitches are transferred from 75 needle to needle and a filling-up point is used for applying a previously-formed stitch to a naked needle, as in such fabrics the widening-wales engage with standing wales.

It will be evident that my improved method 80 of introducing the widening-wales, so as to close the eyelet-hole, may be adapted in the formation of either tubular webs or flat selvage-edged webs produced by reciprocating knitting, as well as in the formation of a web 85 having divided portions connected by floating threads or elongated sinker-wales. The latter method is preferred, however, as it permits of round-and-round knitting and the use of more than one yarn-feed, thus facilitating 90 production and providing for the use of yarns of different color, character, or material for successive single courses of the knitted web.

In the fabric shown in Fig. 1 courses 1, 3, 5, 7, 9, 11, and 13 are composed of yarn of 95 one color, and courses 2, 4, 6, 8, 10, and 12 are composed of yarn of another color.

The needle-plan of a machine upon which a fabric of the character shown in Fig. 1 may be produced is represented diagrammatically 100 in Fig. 6, A representing a segmental set of standing-wale needles, and B B two sets of bordering-wale needles which are movable in respect to the standing-wale needles, as described, so as to start the knitting with a number of the standing-wale needles at each end of the set (the unshaded needles, for instance) out of action, these needles being successively brought into action for widening purposes as the bordering-wale needles are moved so as 110 to permit such introduction. The yarn in this case is laid round and round and crosses the gap between the needles B B.

The needle-plan of a straight machine for producing tubular web widened in the manner described is shown in Fig. 7, in which A A represent two straight sets of standing-wale needles, and B B two sets of bordering-wale needles. The yarn is laid up one side of the machine and down the other, crossing at each 115 end, and its travel may be graduated, so as to be coincident with the active needles, or it may travel throughout the full width of the machine, with suitable take-up for the slack yarn at that end of the machine where the 120 widening is being effected, and in this case the sinker-wale courses uniting the edges will be of normal and uniform length.

The needle-plan of a machine for producing a flat selvaged web widened in accordance with 130

my invention is shown in Fig. 8, in which A represents the standing-wale needles disposed in a single straight bed, and B the ordering-wale needles, one set operating at one end 5 of the needles A and the other at the opposite end of the same. The yarn-guide in this case travels back and forth along the line of needles, having either a graduated movement or means for taking up the slack yarn at each 10 end of the active set of needles, as desired.

When a machine of the type shown in Fig. 6 is employed, the knitting-yarn instead of being carried across the gap between the opposite sets of bordering-needles B may be cut off 15 as it leaves one set and laid in again when it reaches the other set, with the result that short ends of yarn will at each course project from the outermost of the bordering-wales. These short ends may not interfere with the 20 sewing or looping together of the opposite bordering-wales, or they can be readily trimmed off if objectionable in that respect.

Having thus described my invention, I claim and desire to secure by Letters Patent—

25 1. A knitted fabric having a widened portion with bordering-wales, each widening-wale, at the point where it is introduced into the fabric, engaging stitches of two successive courses of one of the bordering-wales.

30 2. A knitted fabric having a widened portion with bordering-wales, each widening-wale, at the point where it is introduced into the fabric, engaging an elongated stitch in one course of one of the bordering-wales, and also 35 a laterally-distended stitch in the next course of said bordering-wale.

30 3. A widened knitted fabric, having the widened portion or portions provided with bordering-wales, and sinker-wale courses projecting beyond the outermost bordering-wale, each widening-wale, at the point where it is introduced into the fabric, engaging with 40 stitches of two adjoining courses of one of the bordering-wales.

45 4. A widened knitted fabric, having the widened portion or portions provided with bordering-wales, and sinker-wale courses projecting beyond the outermost bordering-wale, each widening-wale, at the point where it is introduced into the fabric, engaging with an 50 elongated stitch in one course of one of the bordering-wales, and also with a laterally-distended stitch in the next course of said wale.

55 5. A widened knitted fabric having opposite portions connected by elongated sinker-wale courses, which decrease in length as the widening is effected, the widened portion or portions having bordering-wales, and each

widening-wale, at the point where it is introduced into the fabric, engaging with stitches 60 of two adjoining courses of one of the bordering-wales.

6. A widened knitted fabric having opposite portions connected by elongated sinker-wale courses, which decrease in length as the 65 widening is effected, the widened portion or portions having bordering-wales, and each widening-wale, at the point where it is introduced into the fabric, engaging with an elongated stitch in one course of one of the bordering-wales, and also with a laterally-distended stitch in the next course of said wale. 70

7. The mode herein described of producing a widened knitted fabric, said mode consisting in effecting relative movement of the standing-needle wales and bordering-needle wales, and causing each widening-needle wale, as it is introduced into the fabric, to engage with a previously-formed bordering-needle wale. 75

8. The mode herein described of producing a widened knitted fabric, said mode consisting in effecting relative movement of the standing-needle wales and bordering-needle wales, and causing each widening-needle wale, as it is introduced into the fabric, to engage with previously-formed bordering-needle wales in two successive courses of the fabric. 80

9. The mode herein described of producing a widened knitted fabric, said mode consisting in moving a set of bordering-needle wales in 90 respect to the standing-needle wales, and causing each widening-needle wale, as it is introduced into the fabric, to engage with a previously-formed bordering-needle wale, which has, by the movement of said bordering-needle wales, been brought into position to be 95 thus engaged.

10. The mode herein described of producing a widened knitted fabric, said mode consisting in moving a set of bordering-needle wales in 100 respect to the standing-needle wales, and causing each widening-needle wale, as it is introduced into the fabric, to engage with previously-formed bordering-needle wales in two successive courses of the fabric, which wales 105 have by the movement of the bordering-needle wales, been brought into position to be thus engaged.

In testimony whereof I have signed my name to this specification in the presence of two subscribing witnesses. 110
